(57) **CLAIM**

The ornamental design for a practice device to enable children to simulate skateboarding, as shown and described.

DESCRIPTION

FIG. 1 is a perspective view of the practice device to enable children to simulate skateboarding, showing our new design.

FIG. 2 is a top plan view;

FIG. 3 is a bottom plan view;

FIG. 4 is a front view;

FIG. 5 is a rear view;

FIG. 6 is a side elevational view when viewed from the right side; and,

FIG. 7 is a side elevational view when viewed from the left side.
